1

Common name: Mandarin.

Botanical classification: *Citrus* sp.

Variety denomination: 'Mikanken14'.

BACKGROUND OF THE NEW VARIETY

The present invention relates to a new and distinct variety of mandarin, *Citrus* sp., which has been given the variety denomination 'Mikanken14'.

ORIGIN OF THE VARIETY

The parent varieties are 'Unknown mandarin variety' (male parent) and 'Mikanken4' (female parent) (U.S. Plant patent application Ser. No. 18/944,163), respectively.

The variety was developed and propagated in Uwajima, Ehime, Japan.

The variety was reproduced asexually by vegetative reproduction by top grafting one-year-old scions on rootstocks, in Uwajima, Ehime, Japan. The name of the rootstock is 'MIYAGAWAWASE' (not patented).

In 2005, crossing the parent varieties and collecting seeds to be grown in the next year.

In 2006 and 2007, seeds were planted and grown.

In 2008, scions were grafted on top of root stock.

In 2010, the first fruit was harvested, and lines were primarily selected.

In 2012, lines were secondary selected.

In 2024, breeding was completed with DUS status confirmed (distinct, uniform, and stable), whereby it was confirmed that the instant tree reproduces true to type in successive generations of asexual reproduction, and the variety was named 'Mikanken14'.

(57) ABSTRACT

A new variety of *Citrus* sp. plant named 'Mikanken14' that has vivid orange as the surface predominant color of the fruit, strong orange as main color of the flesh, and very early to early maturity of the fruit for consumption.

3 Drawing Sheets

2

Cultivation of variety does not require special conditions or treatments. The variety is currently mainly intended for fruit production.

5 **SUMMARY OF THE VARIETY**

10 This new mandarin plant 'Mikanken14' has medium orange as the surface predominant color of the fruit, medium orange as main color of the flesh, and very early to early 15 maturity of the fruit for consumption, that distinguish it notably from its female parent 'Mikanken4' (dark orange surface as predominant color of the fruit, dark orange as main color of the flesh, late maturity of the fruit for consumption).

20 Also, 'Mikanken14' has very thin rind thickness of the fruit, absent or very sparse of filling of the core, very small diameter of the core, that distinguish it notably from its 25 comparative variety 'HAREHIME' (not patented in the U.S., plant variety protection granted in Japan) (thin rind thickness of the fruit, sparse of filling of the core, medium diameter of the core).

In addition, the fruit of 'Mikanken14' has the following 30 characteristics: the fruit size is from 150 g to 200 g, the strength of the segment walls is weak, the fruit has no seeds, in early December, the total soluble solids (Brix) of juice are about 15 degrees and the juice acidity is medium, and the time of maturity of the fruit is from late December to January.

Table 1 shows a comparison between the instant variety 'Mikanken14' and Female parent variety 'Mikanken4', as follows (average evaluation):

TABLE 1

Comparison between 'Mikanten14' and 'Mikanten4'

Characteristics	Female parent variety 'Mikanten4' States	Present variety 'Mikanten14' States
Fruit: surface predominant color	Dark orange	Vivid orange
Fruit: main color of flesh	Dark orange	Strong orange
Plant: time of maturity of fruit for consumption	Late	Very early to early

Table 2 shows a comparison between the instant variety 'Mikanten14' and comparative variety 'HAREHIME'

TABLE 2

Comparison between 'Mikanten14' and 'HAREHIME'

Characteristics	Comparative variety 'HAREHIME' States	Present variety 'Mikanten14' States
Fruit: rind thickness	Thin	Very thin
Fruit: filling of core	Sparse	Absent or very sparse
Fruit: diameter of core	Medium	Very small

BRIEF DESCRIPTION OF THE DRAWINGS

In the accompanying drawings, which are as nearly true as is reasonable possible to make in a color illustration of this type:

FIG. 1 is a color photograph showing a general view of an illustrative 12-year old mandarin tree of the variety named 'Mikanten14' bearing fruits.

FIG. 2 is a color photograph showing flowers of 'Mikanten14'.

FIG. 3 is a color photograph showing leaves of 'Mikanten14'.

FIG. 4 is a color photograph showing fruits of 'Mikanten14'.

FIG. 5 is a color photograph showing fruits of 'Mikanten14' and 'Mikanten4', which indicates the difference of fruit: surface predominant color and main color of the flesh.

FIG. 6 is a color photograph showing fruits of 'Mikanten14' and 'HAREHIME', which indicates the difference of the fruit: thickness of rind, filling of the core, diameter of the core.

Due to chemical and/or digital development, processing and printing, the plants or portions of plants depicted in the photographs may or may not be precisely accurate when compared to the actual botanical specimens.

DETAILED DESCRIPTION OF THE INVENTION

Table 3 shows the botanical description of the 'Mikanten14' plants evaluated in 2023 (including the comparison with the reference plants 'Mikanten4' and 'HAREHIME'). The values as provided are average. The ages of the trees evaluated was 13 years after grafted on top of Rootstock, and the location of the trees evaluated was in Uwajima, Ehime, Japan.

Colors are given according to the J.H.S. (Japan Horticultural Society) Color Chart (second edition, 1997 reprint).

BOTANICAL DESCRIPTION

TABLE 3

Botanical description of 'Mikanten 14'			
	Characteristics	States	Values
5	Ploidy	Diploid	
10	Tree: growth habit	Spreading	
	Tree: density of spines	Absent or sparse	
15	Tree: height	2.5 m	
	Tree: spread	3.0 m	
	Tree: trunk diameter (10 cm above the grafted area)	32.5 cm	
	Tree: trunk texture	Rough	
20	Tree: crotch angle	71°	
	Branch: length	11.5 cm	
	Branch: diameter	3.8 cm	
	Branch: texture	Smooth	
	Length of spines	4.7 cm	
25	Leaf blade: length (apical leaflet in case of compound leaf)	Long	11.4 cm
	Leaf blade: width (apical leaflet in case of compound leaf)	Broad	5.1 cm
	Leaf blade: ratio length/width (apical leaflet in case of compound leaf)	Small	2.2
	Leaf blade: shape in cross section (apical leaflet in case of compound leaf)	Intermediate	
30	Leaf blade: twisting	Absent or weak	
	Leaf blade: blistering	Absent or weak	
	Leaf blade: color	Dark green	3509 (JHS Color Chart)
	Leaf blade: undulation of margin	Intermediate	
35	Leaf blade: incisions of margin	Absent	
	Leaf blade: shape of apex	Acute	
	Leaf blade: emargination at tip	Absent	
	Petiole: length	Medium	1.9 cm
	Petiole: presence of wings	Present	
	Varieties with petiole wings present only: petiole: width of wings	Narrow	4.1 mm
40	Flower: diameter of calyx	0.8 cm	
	Flower: length of petal	Short	13.4 mm
	Flower: width of petal	Broad	6.2 mm
	Flower: ratio length/width of petal		2.2
	Flower: length of stamens		9.8 mm
	Anther: color	Pale reddish yellow	2202 JHS Color Chart
	Style: length		7.0 mm
	Inflorescence: clustering of fruits	Absent	
	Fruit: length		5.6 cm
	Fruit: diameter		7.1 cm
	Fruit: ratio length/diameter		1.27
50	Fruit: position of broadest part	At middle	
	Fruit: shape in transverse section	Circular	
	Fruit: general shape of proximal part (excluding neck, collar and depression at stalk end)	Flattened	
	Fruit: presence of neck	Absent	
	Fruit: presence of depression at stalk end	Absent	
	Fruit: presence of constriction at stalk end	Absent	
	Fruit: number of radial grooves at stalk end	Absent or few	0
	Fruit: presence of collar	Absent	
60	Fruit: abscission layer between floral disc and fruit	Absent or weakly developed	
	Fruit: general shape of distal part (excluding nipple, bulging of navel and depression at distal end)	Flattened	
	Fruit: presence of depression at distal end	Present	

US PP37,125 P2

TABLE 3-continued

Botanical description of 'Mikanken 14'		
Characteristics	States	Values
Fruit: depth of depression at distal end		1.3 mm
Fruit: diameter of depression at distal end		9.0 mm
Fruit: presence of areola	Incomplete	
Fruit: type of areola	Smooth	
Fruit: diameter of areola		0.9 cm
Fruit: diameter of stylar scar		1.4 mm
Fruit: persistence of style	None	
Fruit: presence of navel opening	Absent	
Fruit: presence of radial grooves at distal end	Absent	
Fruit: surface: predominant color(s)	Vivid orange	1605 (JHS Color Chart)
Fruit surface: glossiness	Strong	
Fruit surface: roughness	Smooth	
Fruit surface: size of oil glands	All more or less the same size	
Fruit surface: size of larger oil glands	Medium	
Fruit surface: conspicuousness of larger oil glands	Strong	
Fruit surface: presence of pitting and pebbling on oil glands	Pitting and pebbling absent	
Fruit rind: thickness	Very thin	1.5 mm
Fruit rind: adherence of flesh	Weak to medium	
Fruit rind: strength	Medium	
Fruit rind: oiliness	Dry	
Fruit rind: conspicuousness of oil glands on inner surface	Absent or weakly conspicuous	
Fruit: color of albedo	Yellowish white	2502 (JHS Color Chart)
Fruit: density of albedo	Medium	
Fruit: amount of albedo adhering to flesh (strand excluded)	Medium	
Fruit: presence of albedo strands	Present	
Fruit: amount of albedo strands	Medium	
Fruit: main color of flesh	Strong orange	1606 (JHS Color Chart)

TABLE 3-continued

Botanical description of 'Mikanken 14'		
Characteristics	States	Values
Fruit: filling of core	Absent of very sparse	
Fruit: diameter of core	Very small	9.4 mm
Fruit: presence of rudimentary Segments	Absent or very weak	
10 Fruit: number of well-developed segments		11
Fruit: coherence of adjacent segment walls	Medium	
Fruit: strength of segment walls	Weak	
Fruit: length of juice vesicles		4.8 mm
Fruit: thickness of juice vesicles		2.9 mm
15 Fruit conspicuousness of juice vesicle walls	High	
Fruit: coherence of juice vesicles	Medium	
Fruit: presence of navel (viewed internally)	Absent or very rare	
20 Fruit: juiciness	High	
Fruit juice: total soluble solids	High	14.2 (Brix)
Fruit juice: acidity	Medium	1.07
Fruit: strength of fiber	Weak	
Fruit: number of seeds (open pollinated)	Absent or very few	0
Seed: polyembryony	Absent	
25 Plant: time of maturity of fruit for consumption	Very early to early	December
Plant: fruit: parthenocarpy	Present	
Fruit productivity		35 ton/ha

30 Other features of the plant are as follows:

Disease and pest resistance.—Not observed to date.
Tree Hardiness.—USDA Hardiness Zone 9a-9b (until -3° C.).

The invention claimed is:

35 1. A new and distinct variety of *Citrus* sp. plant named 'Mikanken14', substantially as described and illustrated herein.
